ADJUSTABLE ARTICLE SUPPORT

Iverson O. Mitchell, Jr., Washington, D. C.

Application February 18, 1949, Serial No. 77,252

6 Claims. (Cl. 248—160)

1

This invention relates to adjustable article supports.

An object of this invention is to provide adjustable support for articles such as telephone receivers or the like, for supporting the article in a position whereby the user may have the free use of both hands while talking over the telephone.

Another object of this invention is to provide a support of this kind, including a base and an adjustable arm extending from the base, the arm including means whereby the arm may be locked in a selected adjusted position so as to firmly hold the article on the upper or extended end of the arm.

A further object of this invention is to provide a supporting structure of this kind, including electro-magnetic means for locking the adjustable arm in adjusted position and permanent magnetic means for releasing the arm when the electro-magnetic means has been de-energized.

A further object of this invention is to provide an adjustable support of this kind, including spring clips for detachably holding a telephone receiver or the like.

With the above and other objects in view, my invention consists in the arrangement, combination and details of construction disclosed in the drawings and specification, and then more particularly pointed out in the appended claims.

In the drawings,

Figure 1 is a vertical section, partly in detail, of an adjustable support constructed according to an embodiment of this invention.

Figure 2 is a fragmentary vertical section on an enlarged scale, of the lower one of the ball socket members.

Figure 3 is a fragmentary sectional view on an enlarged scale, of a portion of one of the ball sockets and balls,

Figure 4 is a detail side elevation of one of the complementary socket members,

Figure 5 is a fragmentary side elevation of one of the electro-magnetic balls,

Figure 6 is a fragmentary sectional view taken on the line 6—6 of Figure 1,

Figure 7 is a fragmentary sectional view taken transversely across the clamping member at the upper end of the support,

Figure 8 is a diagrammatic view showing the electric circuits embodied in this invention.

Referring to the drawings, the numeral 10 designates generally a base housing which is adapted to have mounted therein batteries 11. The base housing 10 is adapted to be mounted on a suit-

2

able support such as a desk or in a position closely adjacent to a desk, and the base 10 includes a top wall 12 which is formed with openings 13 and 14 through which electric conductors as will be hereinafter described are adapted to be extended.

An adjustable upstanding arm generally designated as 15 is secured to and extends upwardly from the top wall 12. The arm 15 is formed of a lower ball socket member 16 which is formed of complementary half spherical members 17 and 18 having base flanges 19 and 20 respectively which are adapted to be secured by fastening members 21 to the top wall 12. The ball socket member 16 is preferably formed of dielectric material such as plastic or the like and the spherical member 16 is cut off as indicated at 22.

A ball 23 is rotatably mounted in the ball socket 16 and is formed with a plurality of recesses or keepers 24 which are circumferentially spaced about the ball 23. The ball 23 has extending therefrom a shank 25 which is preferably formed integral with the ball 23, and the ball 23 and shank 25 are formed of metal which is adapted to be magnetized upon the closing of the electric circuit to a coil 26 which is wrapped about the shank 25.

A double ball socket link 27 engages a second ball which is carried by a second shank 28 insulated by insulating means 29 from the shank 25. The double ball socket link member 27 is formed of complementary half members connected together by shanks 30, which are secured together by fastening means 31. The shank 28 has wrapped thereabout a coil 32 which is connected in parallel with the coil 26 so that the two coils 26 and 32 will be energized at the same time. Each socket member has mounted in radially disposed recesses 33 metal pins 34 which are adapted to be pulled toward the magnetized balls 23 and into a keeper 24 which is positioned in registry or in alignment with a locking pin 34. It will be understood that it is not necessary that the ball 23 be positioned with the keepers 24 all in registry with a locking pin 34. It is only necessary that one or more of the keepers 24 be in confronting or registering position with respect to a locking pin 34.

When the ball 23 is energized the pin 34 will be drawn inwardly into the keeper 24 so that the ball 23 will thereby be locked against rotation in the socket. Each socket member has disposed in the recesses 33 thereof permanent magnets 35 which have a magnetic pull less than the magnetic pull of the activated core or ball 23. When the coils 26 and 32 are de-energized the perma-

nent magnets 35 will come into operation and will pull the locking pins 34 inwardly into the recesses 33 and out of locking engagement with the keepers 24. There may be as many links including the double ball link members and the double ball socket members as may be desired.

The upper one 16a of the ball socket members has secured thereto a base plate 36, and the plate 36 has secured thereto a pair of spring clips 37 with which a telephone instrument 38 of conventional construction is adapted to be detachably engaged. The upstanding support comprising the balls and sockets is sheathed by means of a flexible tubing 39 which is secured as at 40 to the top wall 12 of the base member 10 and is secured as at 41 to the upper plate member 36. The batteries 11 have connected thereto conductors 42 and 43 which are connected to the coils 26 and 32 in parallel as indicated in Figure 8. A conventional switch 44 is interposed in conductor 43 and is mounted on the top wall 12 so that the electro-magnetic members comprising the shanks 25 and the balls 23 may be energized and locked in their adjusted position to hold the instrument 38 at the desired angular relation for convenient use with the user having the free use of both hands.

In the use and operation of this invention the base 10 is mounted either on a desk or closely adjacent to a desk. Normally the instrument 38 will be engaged with the instrument box but when the user desires to have the free use of both hands in using the instrument 38, the latter may be clamped to the clips 37 by merely pressing the instrument 38 into the clips 37. The support 15 may then be angularly adjusted to the desired angle with respect to the instrument 38 whereupon switch 44 is closed so as to energize the coils 26 and 32. At this time the locking pins 34 will all be drawn inwardly toward the balls 23 and where a keeper 24 is in registry with a locking pin 34, the locking pin will engage in the keeper 24. The support 15 will thereby be locked in its adjusted position. It will, of course, be understood that if desired the manner of locking the links may be reversed from that herein shown, as the electro-magnetic means may be associated with the ball sockets and the locking pins associated with the balls and the latter permanently magnetized. In this latter case the support will be normally in locked position and can be adjusted by closing the circuits to the coils in the sockets for a time sufficient to pull the locking pins to released position.

I do not mean to confine myself to the exact details of construction herein disclosed, but claim all variations falling within the purview of the appended claims.

What I claim is:

1. An adjustable article support comprising a base, a relatively flexible arm extending from said base, an article holder carried by the extended end of said arm, said arm including elec-

tro-magnetic means for effecting rigidity thereof in any adjusted position with respect to said base, and permanent magnet means for releasing said rigidity upon de-energization of said electro-magnetic means.

2. An adjustable article support comprising a base, a relatively flexible arm extending from said base, and an article holder carried by the extended end of said arm, said arm being formed of a plurality of pivotally connected links, and locking pins slidably carried by certain ones of said links, keepers formed in the remaining ones of said links, electro-magnetic means for moving said pins into said keepers to rigidly lock said links together, and permanent magnet means for moving said pins out of said keepers on de-energization of said electro-magnetic means.

3. An adjustable article support comprising a base, a relatively flexible arm extending from said base, and an article holder carried by the extended end of said arm, said arm being formed of a plurality of pivotally connected links, said links comprising alternate ball and socket members, means for releasably locking said members against movement, and permanent magnet means for releasing said locking means.

4. An adjustable article support comprising a base, a relatively flexible arm extending from said base, and an article holder carried by the extended end of said arm, said arm being formed of a plurality of pivotally connected links, said links comprising alternate ball and socket members, electro-magnetic locking means for releasably locking said members against movement, and permanent magnet means for releasing said members for movement relative to each other when said electro-magnetic means has been de-energized.

5. The construction of claim 4 wherein each ball member is provided with a plurality of keeper recesses, and each socket is provided with a plurality of locking pins selectively engageable in said keepers.

6. The structure of claim 5 wherein each pin is seated in a recess in the socket and the permanent magnet means include individual magnets in each socket.
